UNITED STATES PATENT OFFICE.

JAMES H. GRAVELL, OF ELKINS PARK, PENNSYLVANIA.

CONTAINER.

Application filed December 1, 1921. Serial No. 519,035.

To all whom it may concern:

Be it known that I, JAMES H. GRAVELL, a citizen of the United States, and a resident of Elkins Park, in the county of Montgomery and State of Pennsylvania, have invented certain new and useful Improvements in Containers, of which the following is a specification.

My invention relates to containers for holding either liquid or finely divided solids. Although the invention is applicable to containers in general, it is directed more particularly to wooden barrels.

The principal object of my invention is the production of a leak-proof container of simple construction.

A further object of the invention is the production of a container having a construction permitting it to hold a corrosive material without loss of said material when the container is transported or stored.

Generally stated the invention consists in the provision of a container provided with a lining which, when the container is filled with its contents, either a liquid or a finely divided, solid, conforms itself in shape to the shape or irregularities in the shape of the inner wall of the container, said inner wall acting as a support for said lining. The lining itself may be of any suitable material which will vary according to the nature of the contents. I have found in practice that one of the most suitable materials for lining is rubber and although the invention will be described in connection with rubber linings it will be understood that when conditions require, linings made of other materials may also be used.

The invention consists in the novel parts and combinations thereof hereinafter more particularly described and then specified in the claims.

In the accompanying drawings showing a practical embodiment of the invention:

Fig. 1 is a plan view of the sheet of material from which the body of the lining is formed.

Fig. 2 is a perspective view of the body of the lining.

Fig. 3 is a section taken through the body of the lining after the bung fitting has been secured thereto.

Fig. 4 is a plan view of the sheet of material from one of the heads of the lining.

Fig. 5 is a section taken through the con-

tainer after the body of the lining has been inserted therein.

Fig. 6 is a similar view with the lining head in proper position before being pressed into engagement with the body lining by a head of the container.

Fig. 7 is a section taken through the complete container ready for filling.

Fig. 8 is an enlarged section through a portion of the container showing the means for closing the bung fitting.

Fig. 9 is an enlarged section taken through a portion of a modification of the container showing the inclusion of a supplemental lining intermediate the ordinary lining and the body of the barrel.

Fig. 10 is a plan view of a portion of the supplemental lining.

Fig. 11 is a section taken through a modified form of lining.

Referring in detail to the several figures of the drawing:

1 indicates the staves forming the body of a conventional wooden bilge barrel, said staves being provided with crozes 2 adjacent their upper and lower ends for reception of the reduced peripheries or edges of the annular wooden heads 3. The parts are held in position, as ordinarily, by the hoops 4 encircling the stave members 1. One of said stave members is provided with a bung 5.

6 indicates a sheet of thin live rubber which I perforate as at 7, this perforation corresponding in size to the bung 5. The thickness of said rubber may vary to a great extent but I have found from experience that the material known as "dental dam" and weighing about thirteen ounces per square yard constitutes a very satisfactory one for the purpose of the invention.

When lining the barrel in accordance with my invention the sheet of rubber 6 which is slightly greater in width than the height of the barrel and slightly longer than the inner circumference of the barrel is formed into a cylinder 6' as indicated in Fig. 2 and the overlapping ends of said sheet are cemented together. 7' indicates a hollow bung fitting of flexible moulded rubber having an inner annular flange 8 and an outer annular flange 9. The flange 8 is securely cemented to the cylinder 6' around the perforation 7, the cylinder and the bung fitting after completion of this operation being shown in Fig. 3. Some of the upper

hoops 4 of the barrel are then removed to permit removal of the upper head 3 and the cylinder 6 is then inserted in the barrel and the bung fitting 7' inserted within the 5 bung hole 5 whereby the outer annular flange 9 will engage the outer surface of the barrel stave in which the bung hole 5 is provided. The end of the rubber cylinder is then turned over the upper edge of the 10 barrel and held in position by means of suitable weights 10 detachably secured at intervals to the upper edge of the cylinder.

After the above operations have been performed I take a piece or strip of rubber 11 15 shown in Fig. 4 which is preferably of the same thickness as the lining body 6 and of a size more than sufficient to cover the open head of the barrel as shown in Fig. 6. This head lining 11 is then placed over the open 20 head of the barrel and held in place by suitable weights 12 detachably engaging the edge of the head lining. The upper barrel head 3 is then pressed downwardly into the open head of the barrel until the reduced 25 edge engages the upper croze 2 and the barrel hoops which were removed are driven into place, this action tending to press the head lining 11 against the cylindrical body lining 6' by a pinching action and forming a tight 30 seal between the two rubber surfaces. The weights 10 and 12 are then removed and the barrel hoops are further driven down so as to complete the operation on this end of the barrel. The barrel is then turned upside 35 down and the opposite head thereof is removed. The lining is properly positioned with respect to this head, the weights are detachably secured to the edge of the cylindrical lining, another head lining 11 is procured and the operations previously 40 performed and described are repeated, the completed container being shown in Fig. 7. It will now be evident that, after the head linings and body lining have been placed 45 and secured to the barrel by pinching the linings together by insertion of the barrel heads, the three separate lining parts are continuous and in reality form a single lining for the barrel.

In some cases, in order to positively assure a tight joint between the head lining 11 and the cylindrical body lining 6' I apply cement on the contacting rubber surfaces of the two parts before the barrel head 3 is positioned in place.

After the lining has been applied as explained the barrel is turned on its side and filled through the bung fitting 7' in the regular way. When being filled it is usually desirable to hold the bung fitting away from the bung hole 5 by a small wedge so that any air pocketed between the lining body and barrel may escape through the bung hole.

When the barrel is filled the contents

act to expand the lining and press it against the inner surface of the barrel which acts as a support therefor and the lining, being expandible, adapts itself to the shape or irregularities in the shape of the 70 barrel. To seal the barrel I provide a rubber stopper 13 adapted to fit within the bung fitting 7'. Said stopper is provided with a depression 14 and with an annular flange 15 adapted to engage the 75 flange 9 of the bung fitting. When said stopper is pressed home within the bung fitting, removal thereof is prevented by the provision of a locking plate 16 provided with an extension 17 entering and fitting 80 within the depression 14, said locking plate being also provided with a flange 18 secured to the body of the barrel by suitable screws 19.

One of the difficulties in lining barrels 85 with thin rubber is the danger of causing punctures in the rubber by splinters in the wooden barrel. To obviate this difficulty I propose to provide in some cases a supplemental lining 20 made of a splinter- 90 resisting material such as paper which is interposed between the rubber lining hereinbefore described and the inner surface of the heads and body of the barrel. This lining is preferably made of crimped paper as shown in Fig. 10 whereby it will expand and be pressed against the inner surface of the barrel parts when the barrel is filled. The supplemental lining may be 95 made up from three separate parts as in 100 the case of the rubber lining and it may be inserted in the barrel at the same time as the rubber lining in an obvious manner.

After the barrel has been lined the free ends or extensions of the linings which protrude outwardly from the crozes of the barrel may be neatly trimmed or cut off with a knife so that they do not extend beyond the heads 3. This greatly enhances the appearance of the article.

It will be noted that the lining is practically detached from the container itself except where it is held in place by pinching it between the head and the staves of the barrel. It would also be possible and still be within the invention to make a complete lining for the barrel comprising a body portion 21 and head portions 22 as shown in Fig. 11 and providing said lining with extending flanges 23 at the meeting points 115 of said body portions and head portions and pinching said flanges in the crozes of the barrel in the same manner as in the preferred form of the invention.

My method of lining is far superior to 125 the ordinary methods of securing a lining continuously to the interior of a barrel due to the fact that a movement between the various members or staves of the barrel is not directly communicated to the lining. I 130

have noticed, furthermore, that although one or more staves of a barrel has been broken in transit, the lining still remains intact and no leaks result.

5 It will be understood that the invention is not limited to pinching the lining between members of the container but the lining may be fastened to the container at separated places whereby the remaining portions 10 of the lining are free to permit them to expand into contact with the interior wall of the container when the container is filled.

What I claim as my invention is:—

1. A container having a continuous lining of yielding elastic and expansible material like soft rubber made in sections and held in place and joined to one another to complete the lining and form a liquid-tight joint between the sections by pinching 20 lapped surfaces of the material forming said sections between members of the container.

2. A container having a continuous lining of flexible, expansible yieldable and elastic material like soft rubber made in sections, whose meeting edges are secured together and sealed against one another to form a liquid-tight joint by pinching of 25 lapped surfaces of said yieldable elastic material between members of the container.

3. A container having a lining of flexible, elastic and yielding material like soft rubber and comprising a cylindrical body member and head members joined to one 35 another to form a complete lining made liquid-tight at the joints between said members by pinching lapped surfaces of said yielding material between members of the container.

4. A container having a continuous lining formed of sheets of soft rubber in sections, the edges of which extend through the joints of the container and are fastened together to form a complete, continuous lining made liquid-tight at the joints by the 45 pinching of the said yielding material between members of the container at the joints.

5. A container of wood having a composite liquid-tight and splinter-resisting lining comprising layers of paper and soft rubber superposed, the layer of paper lying between the rubber and the inner wall of the container.

6. A container provided with a bung hole, 55 a lining within said container provided with a perforation therein, a bung hole fitting extending through said bung hole and secured to said lining and communicating with said perforation, means for closing said bung hole fitting and means for preventing removal of said closing means.

7. A container provided with a bung hole, a lining within said container provided with a perforation therein, a bung hole fitting extending within said bung hole and com-

municating with said perforation, a stopper fitting within said bung hole fitting and a locking plate secured to said container and engaging said stopper and preventing removal thereof.

8. A container provided with a bung hole, a lining within said container provided with a perforation therein, a bung hole fitting extending through said bung hole and secured to said lining and communicating 70 with said perforation, a flange on said bung hole fitting engaging the outer surface of the container, a hollow stopper entering said bung hole fitting and engaging said flange and a locking plate entering said hollow 80 stopper and secured to said container.

9. A container having a lining of thin, live rubber and a supplemental puncture-resisting lining interposed between the rubber and the inner wall of the container.

10. A container having a rubber lining therein and a supplemental lining of crimped paper interposed between said lining and the container.

11. A barrel having a lining composed 90 of two head members and a body member all of soft rubber pinched at the edges of the barrel body and barrel head by said head to seal the lining, the remaining portions of the lining being free for expansion into 95 contact with and for support by the interior wall of the barrel.

12. A wooden barrel constructed of staves provided with a croze and a wooden head adapted to be held in the croze and having a lining composed of two head members and a body member all of soft rubber pinched together at the croze to seal the lining, the remaining portions of the lining being free for expansion into contact with 100 and for support by the interior wall of the barrel.

13. A container provided with a bung hole, a rubber lining within said container provided with a perforation therein, a bung hole fitting of flexible rubber extending through said bung hole and secured to said lining and communicating with said perforation and means for closing said bung hole fitting.

14. A barrel constructed of staves and having a lining composed of two head members and a body member all of soft rubber pinched at the edges of the barrel body and barrel head by said head to seal the lining, the remaining portions of the lining being free for expansion into contact with 120 and for support by the interior wall of the barrel.

15. A container made in sections and having a lining also made in sections and consisting of sections of elastic material like soft rubber fastened at the joints of the lining between the joints of the sections of the container, the remaining portions of the

lining being free for expansion into contact with and for support by the interior wall of the container.

16. A bilge barrel having a lining composed of elastic and yielding material like soft rubber fastened at lapped surfaces of said material between the barrel body and barrel heads, the remaining portions of the lining being free for expansion into contact with the bilge and other portions of the in-

terior wall of the barrel and for support thereby.

Signed at New York in the county of New York and State of New York this 29th day of November A. D. 1921.
